UNITED STATES PATENT OFFICE.

FRED GROTNRATH, OF MILWAUKEE, WISCONSIN.

TELESCOPIC ASHES-ELEVATOR.

989,143.

Specification of Letters Patent. Patented Apr. 11, 1911.

Application filed September 20, 1909. Serial No. 518,608.

To all whom it may concern:

Be it known that I, FRED GROTNRATH, of Milwaukee, Wisconsin, have invented a Telescopic Ashes-Elevator, of which the following is a specification.

This invention relates to that class of devices used for hoisting ashes from sidewalk-vaults to the pavement, comprising an endless chain with buckets, the lower end of which dips into a boot or pit under the sidewalk into which the ashes are dumped, and the upper end of which is provided with a movable chute into which the buckets throw the ashes as they turn on reaching the top. 10 Such elevators are made collapsible, that is to say, the upper end can be raised and lowered so as to be withdrawn completely into the vault when not in use, the opening in the sidewalk being closed by a trap-door or cover-plate. The structure of such elevators as heretofore constructed has been such that the sliding members which support the top are necessarily so long that in lowering them they strike the bottom of the 20 ash-pit, and in vaults which provide limited headroom between the floor and sidewalk, it is not possible for such construction in many cases to give them a sufficient elongation to elevate the ashes to the necessary 25 height in order to dump them directly into wagons. Hence in such elevators, where the headroom is limited in order to give them proper extension, it becomes necessary to make a deep ash-pit below the floor to receive the lower ends, and this becomes 30 clogged with ashes so as to interfere with the lowering of the top.

The object of this invention is to obviate this disadvantage, and to provide with a 40 head-room however limited beneath the sidewalk an elevator extensible to any height, without lowering the floor-level; and in particular to so arrange it that the lowering of the elevator cannot possibly be interfered 45 with by the presence of the ashes in the pit.

My invention comprises in general a pair of vertical sliding-posts which support the elevator-top, guides for the intermediate portions of said posts, and tubular sockets 50 which are set in vertical holes dug below the floor to whatever depth is necessary in order to accommodate said sliding-posts when the elevator is collapsed. A special feature of this construction is the raising of the upper 55 ends of said tubular sockets to a point above the limit of the ash-pile, whereby the ashes

are prevented from entering the tops of said sockets; and I furthermore provide against ashes entering said sockets by a top-closure for each socket having a central opening 60 therein neatly fitting the post which slides up and down in said socket.

My invention consists further in the constructions and combinations which are hereinafter described and particularly set forth 65 in the claims accompanying this specification.

The nature of my invention will best be understood from a consideration of the accompanying drawings, which illustrate the 70 most improved form thereof, and herein—

Figure 1 is a front elevation of the elevator collapsed, with the sidewalk, trap-doors, floor, ash-pit and tubular sockets shown in longitudinal section; Fig. 2 is a similar view 75 of the elevator extended, the lower portion of the sockets being omitted; Fig. 3 is a longitudinal section through the elevator at one side of the belt, in the position of Fig. 2; Fig. 4 is a side elevation on a larger scale 80 of the lower end of one of the posts and the upper end of the corresponding socket (shown in section) and parts accessory thereto; and Fig. 5 is a transverse section through the same, taken on the plane 85 5.

In these drawings the same part is designated by the same reference-letter or numeral in each figure.

The basement-floor is represented at *a*, the ash-pit at *b*, the sidewalk at *c*, the aperture 90 therein at *d* through which the ashes are elevated, and the trap-doors covering such aperture at *e*; the parts above named being shown merely for the purpose of illustration, and being, of course, subject to differences in form, position and dimensions in different buildings. 95

Between the ash-pit and sidewalk is erected a supporting-frame of four posts *f*, the lower ends of which may rest upon the floor 100 or ash-pit, and the upper ends may be secured in fixed position by a pair of angle-bars *g* which span the opening *d*. Between these frame-posts is mounted the sliding-frame which supports the elevator-top, the 105 same comprising two vertical sliding-posts *h*, connected near their upper ends in rigid relation by cross-bars *i*, *j*, and the lower ends of which are received in a pair of vertical tubular sockets *k*, which are set, as clearly 110 shown in the drawings, in holes or wells bored below the floor of the ash-pit for this

purpose. Both the posts h and the sockets h' may be conveniently made of ordinary iron piping, and it will be noted that the sockets are considerably larger in internal diameter than the diameter of the posts, so as to give room for racks l , one on each post, which serve as means for raising the frame and are engaged by a pair of pinions m mounted on a shaft n turning in bearings n' , which are carried by the frame-posts f ; and the shaft n projects at one end beyond the bearings and carries on said projecting end a worm-gear o (incased), engaged by the worm o' which is turned by means of a crank o^2 , or by power if desired. It will be observed that the upper ends of the sockets are made to rise a considerable distance above the ash-pit, and they are closed with caps h' , through holes in the center of which pass the posts l ; this prevents ashes from entering the sockets and from any way interfering with the raising and lowering of the top-frame. Also, the posts h are provided upon their lower ends with closed pistons h' carrying rubber-gaskets h^2 , which hold the ends of the posts centrally within the sockets and prevent any dust or fragments which might get through the holes in the caps h' into the sockets h from falling below the pistons; so that on raising the posts such accumulation can easily be cleaned out.

Upon the upper ends of the posts h are mounted a pair of bearing-boxes p which carry the upper shaft q of the elevator on which is mounted a sprocket-wheel q' , and directly below is the elevator boot r in which turns the corresponding sprocket-wheel s' upon the driving-shaft s , which turns in bearings s^2 carried by the sockets h , and said shaft may be driven by means of a sprocket-wheel s^3 mounted on one end and a counter-shaft t carrying a driving-pulley t' and a sprocket-wheel t^2 , and the sprocket-wheels s^3 and t^2 being connected by the driving chain t^3 . The lower portion of said chain is protected by a box u rising above the ash-pit a sufficient distance to prevent ashes from getting in at the top thereof.

The upper ends of the posts h are guided by means of two pairs of flanged rollers u mounted upon stub-shafts u' carried by the frame-posts f , as shown, said rollers being of proper form to allow the racks l to pass between them. The elevator-belt or chain v , mounted upon the two sprocket-wheels q' and s' , carries the usual elevating-buckets v' , the form of said chain constituting no part of this present invention. Over the upper end of the chain and wheel q' may be mounted the usual hood w , upon which is mounted a folding-chute x , but these elements also are customary accessories and form no part of this invention.

My construction enables a collapsible elevator to be provided for any desired height

of elevation without reference to the amount of head-room available, besides having the obvious advantage that the rising and falling movements can not be interfered with by the ashes.

Having thus described my invention, what I claim as new and desire to secure by Letters Patent is:

1. In an ashes-elevator, the combination with the top-frame of a pair of vertically moving posts supporting it and tubular sockets receiving said posts, said sockets being set in and projecting below the floor of the ash-pit.
2. In an ashes-elevator, in combination with a top-frame having a vertically sliding post supporting it, a vertical socket set in the floor of the ash-pit and telescopically receiving said post, the upper end of said socket rising above the floor of the ash-pit to a height sufficient to clear the ashes piled therein.
3. A telescopic ashes-elevator comprising in combination with supporting means, a top-frame carrying a shaft and wheel over which passes the elevator chain, an ash boot immediately below said wheel, a second shaft carrying a wheel within said ash-boot, an elevator-belt mounted on the two wheels and carrying means for elevating materials, means for driving one of said shafts, and a vertical socket set in and below the floor of the ash-pit; said top-frame having a vertical post the lower end of which is received in said socket and guided thereby; and means for raising and lowering said post.
4. A telescopic ashes-elevator comprising, in combination, a supporting frame, a rising and falling top-frame having a pair of vertical posts, means on said supporting frame for slidably guiding said posts, a belt-wheel rotatably mounted on the upper end of said top-frame, an ash-boot, a second belt-wheel rotatably mounted therein, an elevator-belt passing around said wheels and carrying means for elevating materials, means for driving one of said wheels, a pair of vertical sockets receiving the ends of said posts and extending above the limit of the ash-pile, and means for raising and lowering said posts.
5. A telescopic ashes-elevator comprising, in combination, a supporting frame, a rising and falling top-frame having a pair of vertical posts, means on said supporting frame for slidably guiding said posts, a belt-wheel rotatably mounted on the upper end of said top-frame, an ash-boot, a second belt-wheel rotatably mounted therein, an elevator-belt passing around said wheels and carrying means for elevating materials, means for driving one of said wheels, a pair of vertical sockets receiving the ends of said posts and extending above the limit of the ash-pile and below the floor of the ash-pit,

and means for raising and lowering said posts.

6. A telescopic ashes-elevator comprising, in combination, a supporting frame, a rising and falling top-frame having a pair of vertical posts, means on said supporting frame for slidably guiding said posts, a belt-wheel rotatably mounted on the upper end of said top-frame, an ash-boot, a second belt-wheel 5 rotatably mounted therein, an elevator-belt passing around said wheels and carrying means for elevating materials, means for driving one of said wheels, a pair of vertical sockets receiving the ends of said posts and 10 extending above the limit of the ash-pile, a pair of racks on the respective posts, a transverse shaft mounted on said supporting frame, means for rotating said shaft, and a pair of gear-wheels mounted on said shaft 15 and engaging the respective racks.

7. In a telescopic ashes-elevator, the combination with a top-frame therefor having a vertical post, of a vertical tubular socket set in the floor of the ash-pit for receiving said 25 post, said post being of smaller diameter than the internal diameter of said socket and having a piston on the lower end thereof fitting the bore of said socket, and a removable perforated cap through which said 30 post passes covering the upper end of said socket.

8. A telescopic ashes-elevator comprising, in combination, a stationary-frame, a top-frame for said elevator comprising a pair 35 of vertical posts each of which carries a rack, guiding rollers mounted on said stationary-frame intermediately of said posts and acting as guides therefor, a belt-wheel rotatably mounted on the upper end of said 40 top-frame, a second belt-wheel rotatably mounted at a point below said top-frame, an elevator-belt passing over said wheels, means for driving said elevator-belt, a pair of vertical tubular sockets receiving the lower ends 45 of said posts and the upper ends of which extend above the upper limit of the ash-pile and the lower ends below the base of the ash-pile, pistons mounted on the lower ends of the respective posts and fitting the 50 bores of the respective sockets, a pair of perforated caps removably mounted on the up-

per ends of said sockets and through which said posts pass, a transverse shaft rotatably mounted on said stationary-frame and carrying gear-wheels engaging said racks, and 55 means for rotating said last-named shaft.

9. A telescopic ashes-elevator comprising in combination a stationary frame, a top frame having vertical posts with racks, a belt wheel rotatably mounted on the upper 60 end of said top frame, a second belt wheel rotatably mounted on a lower plane, an elevator belt passing over said wheels and having elevating means, means for driving said belt, pistons on the lower ends of said posts, 65 sockets in which said pistons work, and means engaging said racks, and means for rotating such means.

10. A telescopic ashes-elevator comprising in combination a stationary frame, a top 70 frame having vertical posts with racks, a belt wheel rotatably mounted on the upper end of said top frame, a second belt wheel rotatably mounted on a lower plane, an elevator belt passing over said wheels 75 and having elevating means, means for driving said belt, pistons on the lower ends of said posts, sockets in which said pistons work, means engaging said racks, means for rotating such means, and guide 80 rollers for the upper ends of said posts.

11. A telescopic ashes-elevator comprising in combination a stationary frame, a top frame having vertical posts with racks, a belt wheel rotatably mounted on the upper 85 end of said top frame, a second belt wheel rotatably mounted on a lower plane, an elevator belt passing over said wheels and having elevating means, means for driving said belt, pistons on the lower ends of said posts, 90 sockets in which said pistons work, means engaging said racks, means for rotating such means, and guide rollers for the upper ends of said posts, said guide rollers being constructed to allow of the passage of said 95 racks.

In witness whereof, I have hereunto set my hand this 15th day of September, 1909.

FRED GROTNRATH.
